SUPPORTING DEVICE

William A. Bedford, Jr., North Scituate, Mass., assignor to United-Carr Fastener Corporation, Cambridge, Mass., a corporation of Massachusetts

Application November 24, 1948, Serial No. 61,882

4 Claims. (Cl. 248—239)

1

This invention relates to shelf supports, and has particular reference to a shelf support which may be inserted into an opening in a supporting wall for locking engagement therein.

The principal object of this invention is to provide an improved shelf support for refrigerators and the like which is adapted to be assembled in a refrigerator wall when access may be had to one side of the wall only.

A further object of the invention is to provide a shelf support comprising wall-engaging members and a shelf-supporting rod which operates in part to support a shelf and in part to effect a greater rigidity in the wall-engaging members.

Other objects and uses of the invention will be apparent from inspection of the specification and claims hereinafter set forth.

For a fuller understanding of the nature and objects of the invention, reference should be had to the following detailed description taken in conjunction with the accompanying drawing in which:

Fig. 1 is a view in elevation, partly in section, of a shelf support embodying the features of the invention;

Fig. 2 is a view in perspective of the component parts of the device illustrated in Fig. 1;

Fig. 3 is a view in elevation of the device of Fig. 1 as viewed from the right of the figure;

Fig. 4 is a sectional view showing the device in final assembly with a support; and

Fig. 5 is a view in elevation, partly in section, of the device illustrating a method of assembling in an opening in a supporting wall.

Referring to the drawing, there is illustrated a shelf support 10 adapted for insertion into an opening 12 in a supporting wall 14. The shelf support 10 comprises a shelf supporting rod 16, having a flange 18 intermediate a hook-shaped shelf-supporting portion 20 and an opposite end portion 22. An attaching member 24, comprises a base element 26 having an opening 28 disposed therein is mounted against the flange 18 on the side nearest the end portion 22. To prevent rotation of the attaching member 24, the end portion 22 of the rod 16 may be provided with a non-circular portion 21 adjacent the flange 18, in which case the opening 28 will be of a corresponding shape to enable the base element 26 of the attaching member 24 to be disposed thereon in nonrotative assembly. An attaching cap 30 having an opening 32 receiving the rod 16 therein is mounted against the flange 18 on the side nearest the hook-shaped portion 20 of the rod 16. The cap 30 preferably has a dished por-

2

tion 30a for receiving a portion of the flange 18 in final assembly of the parts.

The outer periphery of the attaching cap 30 comprises an attaching rim 34 curled over as at 5 36 to engage the base element 26 and thereby retain the attaching cap 30 and the attaching member 24 in fixed relationship on the rod 16 whereby the flange 18 serves to prevent movement of the attaching cap and the attaching member 10 along the rod.

The attaching member 24 also provides a wall-engaging element 38 attached to the upper portion of the base element 26 and a resilient element 40 attached to the lower portion of the 15 base element 26. The wall-engaging element has an outwardly extending portion 42 attached to the base element 26 a predetermined distance from the opening 28, and an upwardly extending portion 44 forming a shoulder 46 which is spaced 20 from the base element 26 a predetermined distance to receive a section of the supporting wall 14 therebetween. An end portion 48 extends downwardly from the shoulder 46 toward the end portion 22 of the supporting rod 16. As 25 shown in Fig. 1, the end portion 48 does not normally touch the rod 16, but is disposed adjacent the rod for support thereby when the shelf support is in assembled position in a supporting wall opening, as will be described in more detail hereinafter.

The resilient element 40 is attached at one end to the lower portion of the base element 26 a predetermined distance from the opening 28, and extends downwardly therefrom forming a shoulder 50 and then upwardly to provide an inclined camming portion 52 which enables the resilient element 40 to snap into engagement with an edge of the supporting wall 16. The free end 54 of the element 40 is disposed adjacent the end portion 22 for engagement with the end portion 22 35 to provide for a stiffer spring action during insertion of the shelf support into the opening 12 in the supporting wall 14. A locking tab 56 integral with the inclined portion 52 of the element 40 40 extends downwardly from the resilient element 40 preferably in substantially the plane of the inclined portion 42. The free end portion 58 of the tab is spaced from the base element 26 and is disposed to engage the inner surface 60 of the 45 supporting wall 14 when the shelf support is assembled in the supporting wall opening.

The method of assembling the device into the opening 12 in the supporting wall 14 is best illustrated by Fig. 5. The wall-engaging element 55 38 is inserted into the opening so that the

shoulder 46 engages the inner surface 60 of the wall 14. Pressure is then applied to the lower portion of the shelf support causing the resilient element 40 to contract a sufficient distance toward the supporting rod 16 to allow the shoulder 50 of the element 40 to pass through the wall opening 12 after which the resilient member will spring back into position to dispose the shoulder 50 behind the inner surface 60 of the wall. At the same time the tab 56, which contracts slightly during movement of the element 40 through the aperture 12, expands to engage the inner surface 60 and lock the resilient element in the opening. During such attachment, the edge of the supporting wall 14 bears against the outwardly extending portion 42 of the wall-engaging element 38 forcing the wall-engaging element 38 downwardly so that the end portion 48 of the leg rests on the end portion 22 of the rod 16, and is thereby provided with vertical support. This action whereby the end portion 48 is moved into engagement with the portion 22 of the rod 16 during attachment of the fastener, is controlled by the distance between the elements 38 and 40 which is normally greater than the corresponding distance across the opening 12. In final attachment the operation of the attaching elements 38 and 40 draws the cap 30 tightly adjacent the outer surface 62 of the wall 14. If desired, a washer 64 may be assembled with the attaching member 24 in a way to seal the space between the curled rim 36 and the panel 14 when the parts are assembled.

A downward force applied to the hook-shaped shelf-supporting portion 20 of the rod 16 effects stresses on the lower portion of the base element 26 in the direction of the outer face 62 of the supporting wall 14 and results in the shoulder 46 of the wall-engaging element 38 being pulled against the face 60 of the supporting wall 14. This force tends to bend the wall-engaging element 38 downwardly to engage the free end 48 of the element 38 with the end portion 22 of the rod. By this action the element 38 is stiffened and rocking forces tending to disengage the element 38 are resisted.

It will be considered that certain modifications of the device are possible within the scope of the invention. The attaching cap 30 may be secured to the base element 26 by any convenient means other than the attaching rim 36. For example, the attaching cap may have punched out tabs, turned inwardly to engage the base member through suitable openings therein.

Although the attaching cap is desirable to provide a neat appearance to the device, it may be omitted entirely in some applications, in which case the flange may also be omitted, and the base element of the attaching member may be secured directly to the shelf supporting rod. If it is desired to have the device readily removable, the tab 56 may be omitted, in which case the device may be removed by a disengaging force applied to the lower portion of the base element 26.

Although my invention is especially adapted for use in refrigerators, it is not limited thereto, as there are many other applications where the device could be used advantageously.

Since certain changes may be made in the device without departing from the scope of the invention, it is intended that all matter contained herein be interpreted in an illustrative and not in a limiting sense.

like for insertion into an opening of a supporting wall for locking engagement therein, the support comprising a shelf-supporting rod having an outer shelf supporting portion and an opposite inner portion, said rod having a flange element intermediate the ends thereof, an attaching member including a base element having a rod-receiving opening therein mounted against the flange on the opposite inner end portion of the rod, an attaching cap having a rod-receiving opening therein mounted against the flange intermediate the outer and inner portions of the rod, means for securing the attaching cap to the base element of the attaching member, and resilient arms extending from said base element in the direction of the inner portion of said rod for engagement behind said wall through said opening whereby said support is secured to said wall, one of said arms providing a curved portion for hooking engagement behind said wall and having its free end directed toward but normally spaced from said rod to provide means for limiting movement of said arms upon mounting said shelf support in such opening, and another of said arms on a side of said rod opposite said one arm having adjacent said base element an outwardly extending portion for snap fastener engagement with an edge of said opening and at its free end an angularly inwardly directed portion for resilient sliding camming engagement with the edge of such wall opening.

2. A shelf support comprising a supporting member having an annular flange, an apertured disc-like attaching member adapted to be mounted on said supporting member in contact with one side of said annular flange, an apertured cap member adapted to be mounted on said supporting member in contact with the opposite side of said annular flange, means for attaching the cap member and the disc-like member together with the annular flange of the supporting member held therebetween, and support-engaging resilient arms associated with the disc-like member and adapted to engage an apertured support to secure the snap fastener assembly thereto, one of said arms having a hook portion adjacent said disc-like member for hooking engagement with the apertured support and having its free end directed toward but normally spaced from said supporting member to provide means for limiting movement of said one arm upon mounting said shelf support in an aperture of such a support and the opposing one of said arms having snap fastener means including an outwardly directed portion for engaging an edge of such an aperture, an angularly inwardly directed portion for sliding camming engagement with an edge of such an aperture, and a shoulder intermediate said inwardly and outwardly directed portions.

3. A snap fastener assembly comprising a supporting rod-like member having intermediate its end an annular flange and an adjacent portion of irregular cross-sectional shape, a disc-like attaching member having an opening corresponding to the irregularly shaped portion of the supporting member and mounted thereon adjacent one side of said annular flange, a cap member having an apertured dished portion and mounted on said supporting member with the dished portion in contact with an opposite edge of the annular flange, means for securing the disc-like member and the cap member together with the annular flange of the supporting member held therebetween, and a pair of support-engaging resilient arm elements associated with said disc-like member and adapted to engage an apertured sup-

I claim:

1. A shelf support for refrigerators and the

75 member and adapted to engage an apertured sup-

port to secure the shelf support device thereto, one of said arm elements having a curved hooked portion for hooking engagement behind the apertured support adjacent an edge of the aperture therein and having its free end directed toward but normally spaced from said rod-like supporting member for limiting movement of said one arm upon mounting said shelf support upon such apertured support, and the other of said arm elements being disposed opposite said arm element and having a shoulder for engagement behind the apertured support adjacent an opposite edge of an aperture therein and a camming portion for sliding engagement with such opposite edge of such aperture.

4. A shelf support comprising a support-engaging member having a surface for engaging a face of a supporting panel adjacent an aperture therein, a rigid stud portion extending substantially normal to and centrally of said support-engaging surface, a shelf supporting portion extending opposite said stud portion, and resilient support panel-engaging arms extending from said support-engaging surface on opposite sides of said

stud, one of said arms providing a curved portion for hooking engagement behind the support panel and having its free end portion directed toward but normally spaced from said stud to provide 5 means for limiting movement of said one arm toward the stud upon mounting said shelf support in an aperture of a support panel, and the opposite one of said arms having adjacent the support-engaging surface an outwardly extending portion for snap fastener engagement with an edge of the support aperture and at its free end an angularly inwardly directed portion for resilient sliding camming engagement with the edge of the support aperture.
